UNITED STATES PATENT OFFICE.

A. C. BARSTOW, OF PROVIDENCE, RHODE ISLAND.

DESIGN FOR A PARLOR-STOVE.

Specification forming part of Design No. 1,821, dated October 6, 1863.

To all whom it may concern:

Be it known that I, A. C. BARSTOW, of Providence, in the county of Providence and State of Rhode Island, have invented or produced a new and original Design for a Base and Top Plate of Sheet-Iron Stoves; and I do hereby declare that the said new design is fully described and represented in the following specification and accompanying drawings, to which reference is hereinafter made.

The figures in the accompanying drawings represent my new design.

Figure 1 is a plan view of the top plate, and Fig. 2 a sectional elevation thereof. Fig. 3 is a vertical section through the center of the base-plate, and Fig. 4 a plan view of the same.

The two parts of a sheet-iron stove herein shown are the cast-iron top and bottom pieces which incase the sheet-iron envelope or fire-chamber. In conformity with the sheet-iron portion the top and bottom are oval. The former is indented or scalloped upon its periphery with a molded border ornamented with dents upon the inner mold. In the center

there is a circular boiler-hole ornamented in a similar fashion with scalloped molding and dented rim at the outside. The cover is molded and raised toward the center with two circular beads and dents to correspond with the general system of ornamentation. The base-plate is designed to form an interior molding and an exterior molding. The interior is a plain oval, the base of which is ornamented. The exterior molding is scalloped in form, and springs from a level base at the foot of the interior molding. This level base extends farther out in front, to act as a recipient for ashes or cinders that may drop out from the stove.

I claim—

The ornamented configuration and design of the top and base plate of sheet-iron stoves, as herein shown and described.

In testimony whereof I have hereunto signed my name before two subscribing witnesses.

A. C. BARSTOW.

Witnesses:

A. POLLOK,

JOSEPH L. COOMBS.
